(57) **CLAIM**

The ornamental design for wire connection terminal case, shown and described.

DESCRIPTION

FIG. 1 is a front perspective view of a wire connection terminal case showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof.

The outermost broken lines immediately adjacent to the full line showing of the claimed design represent the bounds of the claimed design while all other broken lines are directed to environment and are for illustrative purpose only; the broken lines forms no part of the claimed design.
